United States Patent Office

Des. 213,290
Patented Feb. 4, 1969

213,290

BOTTLE

Brooks D. Fuerst, Toledo, Ohio, assignor to Owens-Illinois, Inc., Toledo, Ohio, a corporation of Ohio

Filed Apr. 12, 1968, Ser. No. 11,439

Term of patent 14 years

U.S. Cl. D9—119

Int. Cl. D9—01

FIG. 1

FIG. 2

The side opposite that shown in FIG. 1 is the same in appearance as the side shown.

The dominant features of the design reside in the portions shown in full lines.

I claim:

The ornamental design for a bottle, substantially as shown and described.
